H. W. WEINHART

ELECTRON DISCHARGE DEVICE

Filed Aug. 7, 1919

Inventor:
Howard W. Weinhart

by *J. G. Roberts* Att'y.

UNITED STATES PATENT OFFICE.

HOWARD W. WEINHART, OF ELIZABETH, NEW JERSEY, ASSIGNOR TO WESTERN ELECTRIC COMPANY, INCORPORATED, OF NEW YORK, N. Y., A CORPORATION OF NEW YORK.

ELECTRON-DISCHARGE DEVICE.

Application filed August 7, 1919. Serial No. 315,833.

To all whom it may concern:

Be it known that I, HOWARD W. WEINHART, a citizen of the United States, residing at Elizabeth, in the county of Union, State of New Jersey, have invented certain new and useful Improvements in Electron-Discharge Devices, of which the following is a full, clear, concise, and exact description.

10 The invention relates to electron discharge devices and to improvements in the electrode mounting for such tubes to adapt them for use with high voltages. It has been found that when high voltages are employed for energizing an electron discharge device that a leakage current flows between the wires sealed into the vacuum tube and leading to the various electrodes.

An object of the present invention is to 20 reduce this leakage current to a minimum and also to dispense with the arbor commonly employed for supporting electrodes, whereby a more rugged construction is provided.

25 These objects are accomplished by providing a wide separation for the lead wires, whereby a comparatively high resistance is afforded to a passage of leakage currents. To this end the stem or inwardly projecting neck of the vacuum tube is terminated in a dome, so that the sealing-in points for the leading-in wires may be widely separated. To provide a wider separation of the supporting connections for the electrodes than is usual when the electrodes are supported from the single glass rod or arbor, this arbor is dispensed with, the electrodes being supported from a tubular member which arises from the stem and which 30 forms an extension thereof. The supporting connections for the electrodes, or some of them, are spaced along this tubular portion at intervals great enough to prevent any substantial or serious flow of leakage currents.

For further details of the invention, reference may be made to the drawings in which the figure illustrates in perspective a vacuum tube embodying the features of this 35 invention.

Referring in detail to the drawing, the vacuum tube 1 is provided with the stem or inwardly projecting neck 2 which terminates in a dome 3. Arising from the 40 dome and concentric therewith and with the

axis of the tube, is the tubular portion 4 which serves as a support for one or more of the electrodes. In this case the anode 5 and grid 6 are supported from the tubular portion 4. For this purpose the anode 5 which may be cylindrical as shown, surrounding the helical grid 6 and helical cathode 7, is provided with the supporting arms 8, 9 and 10 extending therefrom and suitably fastened thereto, for instance, by 45 welding. The supporting arms 8, 9 and 10 for the anode 5 are clamped to the exterior of the tubular portion 4 in a suitable manner, for instance, by a metallic band 11 held in place by a wrapping 12 of wire. 50

The grid is similarly provided with arms 13 and 14 which are clamped in place below band 11 by the metallic band 15 and a wrapping 16 of wire thereon. The filamentary cathode is supported at one end 55 by the wire or rod 17, extending within the tubular portion 4, and which forms an extension of the lead wire 18. The other end of this filament is supported by the arm 19 which is sealed into a glass rod 20 arising 60 from the stem 2.

The leading-in wire 21 for the anode 5 is sealed into the dome at a point 22. The leading-in wires 23, 24 for the cathode are sealed into the dome at the points 25 and 65 26 respectively. The grid is provided with a leading-in wire 27 which is sealed into the dome at the point 28. These points of sealing-in are widely separated so that the leakage currents therebetween are reduced 70 to a safe minimum. A wide separation is also provided for the supporting connections 11-12 and 15-16 for the anode and grid respectively.

What is claimed is:

1. A vacuum tube comprising an inwardly projecting portion, a cathode, a grid surrounding said cathode, metallic supporting members extending from said grid, and means for clamping said members to the 75 outer surface of said inwardly projecting portion.

2. A vacuum tube comprising an inwardly projecting tubular portion, a cylindrical grid, supporting members extending from 80 said grid, and a band for clamping said members to said tubular portion.

3. A vacuum tube comprising cathode, anode and control electrodes, supporting members extending from a plurality of said 85 90 95 100 105 110

2
electrodes, and bands for clamping said members to portions of said tube.

4. An electron discharge device comprising a vessel having a reentrant stem, a tubular member projecting from said stem into the interior of the vessel, a plurality of concentric electrodes spaced from the end of said tubular member, connections extending from the exterior of said tubular member to certain of said electrodes, and a lead wire for another of said electrodes arranged substantially coaxial with said tubular member.

5. A vacuum tube comprising an inwardly projecting neck, a tubular portion arising therefrom, an electrode, means for clamping said electrode to said tubular portion, a lead to said electrode extending with-

in said tubular portion, and a second lead to said electrode extending outside of said 20 tubular portion.

6. A vacuum tube comprising a stem, a tubular extension coaxial with said stem, a plurality of electrodes arranged beyond the end of said tubular member, metallic members 25 attached to the exterior of said tubular member and supporting certain of said electrodes, lead wires for said electrodes attached to said metallic members, and a lead wire for another of said electrodes arranged coaxial of said tubular extension.

In witness whereof, I hereunto subscribe my name this 25th day of July A. D., 1919.

HOWARD W. WEINHART.
